CLAIM

I claim the ornamental design of the tummy liner, as shown.

DESCRIPTION

FIG. 1 is a front elevation view of the tummy liner.

FIG. 2 is a left side elevation view of the tummy liner of FIG. 1.

FIG. 3 is a top plan view of the tummy liner of FIG. 1; and, FIG. 4 is a bottom plan view of the tummy liner of FIG. 1. The broken lines shown in the drawings indicate structure and features which form no part of the claimed design.
